UNITED STATES PATENT OFFICE.

JAMES ELMER FOSTER AND CHARLES FLETCHER RICHEY, OF FRANKLIN,
PENNSYLVANIA.

PUMP-ROD GRIP.

SPECIFICATION forming part of Letters Patent No. 673,679, dated May 7, 1901.

Application filed January 28, 1901. Serial No. 45,046. (No model.)

To all whom it may concern:

Be it known that we, JAMES ELMER FOSTER and CHARLES FLETCHER RICHEY, citizens of the United States, and residents of Franklin, 5 in the county of Venango and State of Pennsylvania, have invented a new and Improved Pump-Rod Grip, of which the following is a full, clear, and exact description.

This invention relates to improvements in devices for gripping pump-rods or other rods or pipes; and the object is to provide a device of this character of simple construction and so arranged that it may be easily attached to a rod or pipe and operated without 15 danger of bending the rod or pipe.

We will describe a pump-rod grip embodying our invention and then point out the novel features in the appended claims.

Reference is to be had to the accompanying 20 drawings, forming a part of this specification, in which similar characters of reference indicate corresponding parts in all the figures.

Figure 1 is a side view, partly in section, of a grip embodying our invention. Fig. 2 is a 25 top view thereof. Fig. 3 is a plan view, partly in section, of the grip-frame; and Fig. 4 is a side view of one of the gripping-jaws.

The frame of the gripping device consists 30 of two side pieces 1 and 2, from one of which a pin 3 extends through an opening in the other side piece and is held by means of a cross-pin 4 through said pin 3 and engaging with the outer surface of the side piece. Mounted to swing on the pin 3 between the 35 side pieces is a clamping-jaw 5, having a cam-shaped inner end to engage with a rod or pipe and having an outwardly-extended stem 6, provided with an eye in which is engaged a section of a chain 7, the upper end of said 40 chain-section being connected to a ring 8, with which a tackle is designed to be engaged. Coacting with the jaw 5 is a removable jaw 9, having a cam-shaped inner end and provided with a stem 10, through the eye of which 45 a chain-section 11 extends to the ring 8. The removable jaw 9 is mounted to swing on lugs 12 and 13, extended inward from the side pieces 1 and 2. These lugs are designed to engage in channels 14, formed in the opposite 50 sides of the jaw 9 and opening downward and outward. The outer edges of these channels

are provided with inwardly-extended flanges 15 to engage against the inner sides of the heads 16, formed on the lugs. This, while permitting the jaw to swing freely on the lugs, 55 will prevent the side pieces of the frame from spreading outward relatively to the jaw.

This device is intended mainly to make connections between tackle-boxes and oil-well rod lines. When there is more than one 60 oil-well on a lease, it is necessary to stretch iron rods from the well to the pumping power, which is located at some central point on the lease. The lines are given a backward-and-forward motion, which works the rods up and down in the well, and the rods sometimes 65 break, allowing the rods or lines to sag down between the carriers, which are about thirty feet apart, and in order to repair a rod it is necessary to pull the two ends together and 70 hold them until repaired. This operation not only takes up all the slack of the iron, but must lift the rods in the well, which cannot be done with a rod or chain hitch on the rod, 75 as it would be almost impossible to make a rod or chain hitch hold, and if it did it would kink the iron line, which would cause it to break. A device embodying our invention will not cause said bending or kinking. To attach the gripping device to a rod or pipe, 80 the removable jaw 9 may be lifted off the lugs 12 and 13, and then the frame members passed along the opposite sides of the pipe and the jaw 9 replaced.

Having thus described our invention, we 85 claim as new and desire to secure by Letters Patent—

1. A rod or pipe gripping device, comprising a frame having side members, a gripping-jaw pivoted between said side members, 90 headed lugs extended inward from said side members, the jaw having channels in its opposite sides to receive said lugs, and flanges extended from the sides of the channels for engaging the heads of the lugs, substantially 95 as specified.

2. A gripping device, comprising a frame having opposite side members, a jaw pivoted between said side members, lugs extended inward from said side members near one end, 100 the ends of said lugs being headed, a jaw having outwardly-opening channels in its op-

posite sides for receiving said lugs, and flanges extended inward from said channels for engaging with the heads of the lugs, substantially as specified.

5 3. A gripping device, comprising a frame having opposite side members, a jaw pivoted between said side members and having an outwardly-extended stem, headed lugs extended inward from said side members, a jaw 10 having channels in its opposite sides to receive said lugs, and flanges on the walls of said channels for engaging with the heads of

the lugs, the said last-named jaw having an outwardly-extended stem, and tackle-attaching devices connecting with said stems, substantially as specified. 15

In testimony whereof we have signed our names to this specification in the presence of two subscribing witnesses.

JAMES ELMER FOSTER.

CHARLES FLETCHER RICHEY.
